DESIGN FOR A PAJAMA SHIRT OR SIMILAR ARTICLE

Robert S. Terry, Utica, N. Y.

Application June 2, 1939, Serial No. 85,305

Term of patent 14 years

To all whom it may concern:

Be it known that I, Robert S. Terry, a citizen of the United States, residing at Utica, in the county of Oneida and State of New York, have invented a new, original, and ornamental Design for a Pajama Shirt or Similar Article, of which the following is a specification, reference being had to the accompanying drawing, forming a part thereof.

Fig. 1 is a view in front elevation of a shirt showing my new design;

Fig. 2 is a view in side elevation of the shirt shown in Figure 1.

I claim:

The ornamental design for a pajama shirt or similar article, substantially as shown.

ROBERT S. TERRY.
